EJECTOR

Ralph R. Boyles and Edward A. Wilhelm, St. Paul, Minn., assignors to Waterous Company, St. Paul, Minn., a corporation of Minnesota

Application May 2, 1942, Serial No. 441,542.

2 Claims. (Cl. 230—95)

Our invention relates to an improvement in ejector of a type particularly designed for utilizing the exhaust pressure generated by an internal combustion engine. Such an ejector is particularly useful for such purposes as exhausting the air from centrifugal pumps in priming the same. Such pumps are often used in conjunction with internal combustion engines in fire fighting equipment and the like.

The object of the present invention is to provide an ejector capable of a high degree of efficiency in such a pump priming operation. It is often necessary to draw water from a source of supply considerably below the level of the pump, and the ejector must be sufficiently effective to prime the centrifugal pump under such conditions.

An object of the present invention lies in the formation of the ejector for the particular shape and size of the same. If the ejector is of improper size, it will not function efficiently for its prescribed purpose. For example, if the ejector nozzle is too large compared to the engine with which it is used, the exhaust pressure obtainable from the engine is insufficient to produce the necessary suction. On the other hand, if the nozzle diameter is too small excessive back pressure is created, which might cause injury to the engine. We have thus found that the size and shape of the ejector bears a definite relation to the particular motor to which it is connected.

This ejector nozzle is tapered from its entrance end to a point intermediate the ends of the nozzle. From this point the nozzle tapers outwardly toward the outlet of the nozzle, the degree of taper increasing near the outlet end thereof. This construction thereby presents a nozzle passage which is constructed the maximum amount at a point intermediate the ends of the nozzle and allows expansion of the gases beyond this point, greatly increasing the efficiency of the nozzle.

A further feature of the present invention lies in the shape of the bore within which the exhaust nozzle is positioned. This nozzle is so shaped as to be of smallest diameter at a point forwardly from the outlet of the ejector nozzle. The bore tapers outwardly toward the end or outlet of the ejector to allow a gradual expansion of the gases. This construction has been found extremely efficient for its prescribed purpose.

A further feature of the present invention lies in the provision of a double seated valve which is pivotally mounted to pivot from one extreme position in which the ejector is cut off to a second position in which the outlet exhaust is cut off.

The valve is interposed between the internal combustion engine exhaust pipe leading to the engine, the engine muffler, and the ejector. The gases from the engine may thus be selectively directed either through the muffler or through the ejector and in either position of the valve the element through which the exhaust is not directed is cut off from receiving any of the exhaust.

These and other objects and novel features of our invention will be more clearly and fully set forth in the following specification and claims.

In the drawings forming a part of our specification:

Figure 1 is a front elevational view of an internal combustion engine having our ejector and valve connected thereto.

Figure 2 is a side elevational view of the engine and ejector showing the relationship of the ejector to the centrifugal pump and to the engine.

Figure 3 is an elevational view of the ejector and valve unit.

Figure 4 is a vertical cross-sectional view through the ejector and valve unit, the position of the section being indicated by the line 4—4 of Figure 3.

Figure 5 is a cross-sectional view through the valve, the position of the section being indicated by the line 5—5 of Figure 3.

Figure 6 is a top plan view of the ejector.

Figure 7 is a vertical section through the ejector, the position of the section being indicated by the line 7—7 of Figure 6.

Figure 8 is a vertical section through the ejector nozzle.

Figure 9 is a vertical section through the ejector casing, the position of the section being indicated by the line 9—9 of Figure 6.

Figure 1 of the drawings illustrates an engine of a common type, indicated in general by the letter A. This engine is an eight cylinder engine having two banks of cylinders 10 and 11, each of which is provided with an exhaust pipe which conducts the exhaust from the cylinders. The cylinder 10 is provided with the common exhaust manifold 12, while the cylinders 11 are provided with the common exhaust manifold 13. These manifolds 12 and 13 are connected together at 14, as illustrated in Figure 2 of the drawings, and conduct the exhaust gases through the elbow 15.

The elbow 15 communicates with the tubular exhaust pipe 16, which in the form illustrated, extends vertically from the elbow 15. Secured to the top of the pipe 16, we provide the valve casting B, which communicates with the ejector C.

and also with an elbow 17, which communicates with the engine muffler 19.

The centrifugal pump D is secured to the motor housing to be rotated thereby. The pump D may be of any suitable type, and is shown having a central intake port 20 and an outlet 21. The pump outlet 21 is controlled by the valve within the valve casing 22, which in turn is manually operated by the valve operating lever 23. A flexible or rigid intake pipe 24 communicates with a suitable source of supply of liquid to be pumped, and the outlet pipe 21 communicates through the valve 22 to the tubular member 25 through which may pass the pumped liquid.

A suction connection 26 is connected to the pump casing at any suitable position, such as to the top of the intake passage 20. The other end of this suction conduit 26 is shown in Figure 3 of the drawings as connected to the suction chamber of the ejector C, as will be later described in detail.

The valve casing B is provided with an inlet opening 27 which communicates with the exhaust pipe 16 and which is secured thereto by any suitable means. Axially aligned with the inlet opening 27 we provide an outlet opening 29. A valve seat 30 is bolted to the casing body 31 of the valve B and is secured thereto by any suitable means, such as by the cap screws 32. The elbow 17 communicating with the muffler 19 is provided with a flange 33 which is secured by cap screws 34 or other suitable means to the valve seat 30.

At right angles to the outlet passage 29, we provide a second outlet passage 35. An elbow 36 is provided with a flange 37 which abuts against the casing body 31 to form a valve seat. The elbow 36 is held in place by any suitable means, such as by the cap screws 39. The passage 40 through the elbow 36 is of smaller diameter than the outlet opening 35 so that a shoulder 41 is provided against which the valve may seat.

A shaft 42 extends through the body 31 of the valve B. An arm 43 is provided with a collar 44 keyed to the shaft 42. The arm 43 extends between a pair of connecting arms 45 of the valve element 46. The arms 45 are pivotally attached to the arm 43 by means of a pivot 47 which extends through the arms 43 and 45. A circular valve 49 is provided on one end of the connecting arms 45 designed to fit against the valve seat shoulders 41, and a second circular valve element 50 is secured to the opposite end of the arms 45 to seat against the valve seat 30. As illustrated in Figure 4 of the drawings, the passage 51 through the valve seat 30 is of smaller diameter than the outlet passage 29, so as to provide a shoulder against which the valve element 50 may engage.

In order to hold the valve 46 in either extreme position, a collar 52 is secured to the shaft 42 by means of a set screw 53, or by other suitable means. This collar 52 is provided with an arm 54 and an arm 48 by means of which the collar may if desired be pivoted. A boss 55 projects outwardly from each side of the valve casing body 31. A stub shaft 56 is threadably rotatably mounted in the boss 55. A rod 57 extends through the shaft 56 and a pivot 59 on one end of the rod 57 extends through the arm 54. A spring 60 encircles the rod 57 thereby exerting pressure against the arm 54 to force this arm away from the shaft 56. This arm 54 is rotatable with the shaft to pass through dead center so that when the shaft 42 is in position to urge the valve 46 against the shoulder 52, the spring 57 assists this

action and locks the valve in this position. However, when the valve 46 is in position against the shoulder 41, the spring 57 also locks the valve in this adjusted position. A universal joint 58 is provided in the shaft 42. The position of the collar 52, arm 57, spring 60, and the stub shaft 56 may be reversed in position with the universal joint 58 if desired to place the spring on the opposite side of the valve casing, and to make the valve operable from the opposite side.

When the valve element 46 is in the position illustrated in full lines in Figure 4 of the drawings, the passage to the muffler 19 is closed so that the exhaust gases from the engine A are directed through the ejector C. When the valve element 46 is in the position illustrated in dotted outline in Figure 4 of the drawings, the exhaust gases from the motor A are directed through the elbow 17 and the muffler 19.

The elbow 36 is provided at its outlet end with a flange 61. A similar flange 62 is provided at the upper extremity of the ejector C. The flanges 61 and 62 are clamped together by cap screws 63 or other similar means. The ejector C includes an elongated tubular body 64 which is open at its upper and lower ends. With reference to Figures 6 through 9, it will be noted that a tubular inlet passage 65 is provided which is preferably axially aligned with the passage 40 through the elbow 36. An enlarged suction chamber 67 is provided which is equipped with an inlet opening 69 to accommodate the suction connection 26 connected to a priming valve 68, then to the centrifugal pump. An axially aligned bore 70 extends through the tubular body 64. This bore 70 includes an inwardly tapering entrance portion 71, a substantially cylindrical intermediate portion 72, and an outwardly tapered outlet portion 73. The size and shape of the bore 70 is of considerable importance, as will be later described in detail.

A circular recess 74 is provided at the upper extremity of the inlet passage 65 to receive the circular flange 66 of the ejector nozzle 67. The nozzle 67 is preferably tapered on its outer surface from the larger diameter end adjacent the flange 66 to the nozzle outlet 75. A nozzle passage 76 extends through the nozzle 67, and the shape of this passage 76 forms an important part of the present invention.

The nozzle passage 76 includes an inwardly tapered entrance portion 77 which leads to the most constricted area 79 of the nozzle. An outwardly tapering passage 80 communicates with the inwardly tapering passage 77, and this passage portion 80 extends to a short distance from the outlet end 75 of the nozzle. An outwardly flaring passage portion 81 communicates with the passage 80 and extends to the outlet end of the nozzle. Thus the passage 77 tapers inwardly to a point intermediate the ends of the nozzle and from this point to the outlet of the nozzle tapers outwardly, first gradually, and finally at an increased angle.

We have found that the sizes and proportions of the ejector have a direct bearing on the size of the engine with which the ejector is used. In other words, we have found that the area of the exhaust nozzle at its most constricted point should be from .00087 times the maximum brake horsepower to .0035 times the maximum brake horsepower. If the area is less than this amount the back pressure against the engine is too great to permit efficient operation of the engine. On the other hand, if the area of the nozzle is

greater than this amount, the maximum suction will not be created. Accordingly, if the maximum brake horsepower of the engine is multiplied by .00087 and again by .0035 the limits of the area in square inches will be given.

Once the area of the nozzle is known the diameter of the nozzle may be determined from the formula area equals $D^2/4$. This will provide the diameter indicated in the figures by the letter F. In the use of the letter F, it should be considered to be the diameter of a circular area in square inches of from .00087 to .0035 times the maximum brake horsepower.

We have found that the following ejector dimensions may be based upon the diameter of the ejector nozzle. The dimensions to which the various letters refer may be noted in Figures 8 and 9 of the drawings.

G is preferably $6.3 \times F$, and may vary from 3 to $9 \times F$.

H equals $3 \times F$, and may vary from $1\frac{1}{2}$ to $4\frac{1}{2} \times F$.

J equals $3.3 \times F$, and may vary from $1\frac{1}{2}$ to $4\frac{1}{2} \times F$.

K equals $.6 \times F$, and may vary from .3 F to .9 F.

L equals $1.25 \times F$, and may vary from 1.125 F to 1.375 F.

N equals substantially $10 \times F$ and may vary from 7.5 F to 12.5 F.

O equals 1.3 to 1.7 F.

P equals substantially $N/5$.

Q equals substantially $N/4.4$.

R equals substantially $N/1.75$.

Angle a equals $\frac{1}{2}^\circ$, and may vary from $\frac{1}{4}^\circ$ to 3° .

Angle b equals 8° , and may vary from 5° to 10° .

Angle c equals $3\frac{3}{4}^\circ$, and may vary from 2° to 6° .

Angle d equals $2\frac{3}{4}^\circ$, and may vary from 1° to 5° .

Angle e equals $4\frac{1}{2}^\circ$, and may vary from 3° to 7° .

We have found that these dimensions provide an efficient ejector which is correctly shaped in proportion to the motor on which it is used. The constriction of the exhaust nozzle at a point intermediate its ends permits a gradual expansion of the gases as they pass through the ejector, thus more effectively drawing air from the suction chamber. We have found our ejector to be extremely desirable for its prescribed purpose and that it will act to prime a pump even though the pump is positioned a considerable distance above the source of liquid supply.

In accordance with the patent statutes, we have 50

described the principles of construction and operation of our ejector, and while we have endeavored to set forth the best embodiments thereof, we desire to have it understood that obvious changes may be made within the scope of the following claims without departing from the spirit of our invention.

We claim:

1. A suction mechanism comprising an ejector secured to the exhaust pipe of an internal combustion engine of known maximum brake horsepower, which engine functions as a source of fluid pressure for operating the ejector, said ejector including a nozzle having a continuously tapered passage therethrough, said passage including an inwardly tapered inlet portion and an outwardly tapered intermediate portion, and an outwardly flared outlet portion, a bore extending forwardly from said nozzle providing a combining tube in alignment with the nozzle discharge, and a suction chamber encircling said nozzle, the smallest inner area of said nozzle being in square inches from .00087 times the maximum brake horsepower of the engine to .0035 times the maximum brake horsepower of the engine.

2. A suction mechanism comprising an ejector connected to the exhaust of an internal combustion engine of known maximum brake horsepower, the ejector including a nozzle having a continuously tapered passage therethrough, a tubular member having a bore extending forwardly from the forward end of said nozzle providing a combining tube in alignment with the nozzle discharge and a suction chamber encircling the nozzle and communicating with the rear end of the bore, the nozzle including an inwardly tapered inlet portion and an outwardly tapered outlet portion, the area of the nozzle passage at its smallest diameter being in square inches from .00087 times the maximum brake horsepower of the engine to .0035 times the maximum brake horsepower of the engine, the inlet portion tapering at an angle of from 2 to 6 degrees and the outlet portion of said nozzle being tapered at an angle of from $\frac{1}{4}$ to 3 degrees and a flared end of greater taper at the outlet extremity of said nozzle.

RALPH R. BOYLES.
EDWARD A. WILHELM.
